UNITED STATES PATENT OFFICE.

JOHN H. SATTLER, OF SAN FRANCISCO, CALIFORNIA.

COMBINED COAL AND GAS STOVE.

1,317,397.

Specification of Letters Patent. Patented Sept. 30, 1919.

Application filed July 11, 1917. Serial No. 179,844.

To all whom it may concern:

Be it known that I, JOHN H. SATTLER, a citizen of the United States, and a resident of the city and county of San Francisco and 5 State of California, have invented a new and useful Combined Coal and Gas Stove, of which the following is a specification.

The invention relates to stoves which may be operated with gas or with coal or wood. 10 An object of the invention is to provide in a stove of the class described, an oven which is efficiently and properly heated either by the gas or coal fire.

Another object of the invention is to provide a stove in which the combustion of the 15 gas is completed before entering the oven.

A further object of the invention is to provide a stove of the class described having a gas combustion chamber freely open 20 to the atmosphere.

The invention possesses other advantageous features, some of which, with the foregoing, will be set forth at length in the following description where I shall outline in 25 full that form of the invention which I have selected for illustration in the drawings accompanying and forming part of the present specification. In said drawings I have shown one specific form of my invention, but 30 it is to be understood that the invention, as expressed in the claims, may be embodied in a plurality of forms.

Referring to said drawings:

Figure 1 is a vertical section of one form 35 of combined coal and gas stove of my invention.

Fig. 2 is a vertical section taken on the line 2—2, Fig. 1.

Fig. 3 is a horizontal section taken on 40 the line 3—3, Fig. 2.

The present invention relates particularly to the construction and arrangement of the oven, flues and gas burner within the stove, so that the oven is properly heated when 45 either the gas or the coal fire is being used. The heat for baking or roasting is applied differently when coal is burned than when gas is burned. When coal is used as fuel, the food in the oven is heated by radiation, 50 since the products of combustion do not come into contact with the food. When gas is employed, the food is heated by direct

contact with the products of combustion, which enter the oven. In accordance with 55 my invention, I arrange the gas burner in a large combustion chamber, freely open to the atmosphere and arranged below the main bottom of the stove and provide flues for conducting the gases of complete combustion directly into the oven. This not only insures complete combustion of the gas, but prevents transfer of heat to the oven by radiation through the bottom lining, a condition which causes food in the oven to burn 60 on the bottom.

The stove of my invention is provided with a suitable fire box 2, provided with a grate 3, for the burning of coal, wood or other fuel. From the fire box, the products 70 of combustion pass into the chamber or flue 4 formed between the top 5 of the stove and the top oven plate 6. From this chamber the gases may pass into the flue 7, which is connected directly to the chimney. The 75 passage between the chamber 4 and the flue 7 is controlled by the damper 8 which when closed causes the gases to pass down through the back flue 9 into the bottom flue 12. The 80 wall or plate 11 which separates the flues 7 and 9 extends into the bottom flue 12 so that the gases pass forward in the bottom flue, around the end of the wall and back into the flue 7, whence they pass up the chimney. 85

The bottom flue occurs between the bottom oven plate 13 and the main bottom 14 of the stove.

The oven is closed at the sides by the front oven plate 15 and the back oven plate 16 90 and these plates are spaced from the main bottom 14 of the stove and extend down below said main bottom, and being spaced from said bottom and from the side walls 17 of the bottom flue, form passages 18 connecting the chamber below the bottom of the stove with the oven. These passages 18 are controlled by dampers 19 which are operated from the front of the stove. The front and back oven plates 15 and 16 extend 100 downward below the main bottom 14 of the stove and together with the main bottom and the back wall 22, inclose a chamber 21, in which the gas burner 23 is arranged, and between the burner and the 105

main bottom 14 is a deflecting plate 24, which protects the main bottom from the direct heat of the flame. When the gas burner is not used, the dampers 19 are closed, but when the gas burner is used, the dampers 19 are opened, permitting the gases of combustion and heated air to pass through the passages 18 into the oven. The chamber 21 is large and 10 is open at the bottom and sufficient air is therefore provided to complete the combustion of the gas before entering the oven. The downward extension of the front and back oven plates 15 and 16 prevent any loss 15 of heat by radiation and also serve to form a broiling chamber, racks 25 being provided for that purpose.

The oven is provided with linings 26 at the sides, which are apertured to allow the 20 hot gases to freely enter the oven, the linings 26 being preferably alined with the side walls 17 of the bottom flue. The back lining 27 provides a chamber between the oven and the main back 28 of the stove and the 25 top lining 29 forms a passage 31 below the top of the oven. The top lining 29 is provided at its forward end with a plurality of apertures 32 connecting the oven with the passage 31 and the hot gases discharge from 30 the passage 31 into the flue 7 through the apertures 33 formed in the main back 28 of the stove.

The side and front walls 34 of the stove preferably extend down to the same plane 35 as the bottom of the plates 15 and 16 and the stove is supported on legs to give free access of air to the combustion chamber 21.

I claim:

1. In a combined coal and gas stove, a 40 front oven plate, a back oven plate and a bottom oven plate inclosing an oven, a flue for the gases of combustion of the coal fire arranged below said bottom oven plate and being of less width than the oven, the side 45 walls of the flue being spaced from the front and back oven plates, whereby flues are provided between the front and back oven plates and the side walls of the coal gas flue and a gas burner arranged below said coal 50 gas flue.

2. In a combined coal and gas stove, a front oven plate, a back oven plate and a bottom oven plate inclosing an oven, a flue for the gases of combustion of the coal fire 55 arranged below said bottom oven plate and being of less width than the oven, the side walls of the flue being spaced from the front and back oven plates, whereby flues are provided between the front and back 60 oven plates and the side walls of the coal gas flue, a gas burner arranged below said coal gas flue and dampers arranged in said flues between the front and back oven plates and the side walls of the coal gas flue.

3. In a combined coal and gas stove, a 65 front oven plate, a back oven plate and a bottom oven plate inclosing an oven, a flue for the gases of combustion of the coal fire arranged below said bottom oven plate and being of less width than the oven, the side 70 walls of the flue being spaced from the front and back oven plates and the side walls of the coal gas flue, a gas burner arranged below said coal gas flue and apertured linings in said oven alined with the side walls of 75 said coal gas flue.

4. In a combined coal and gas stove, an oven, a flue of less width than said oven for the gases of combustion of the coal fire arranged below said oven, front and back 80 oven plates spaced from the side walls of the flue and extending upwardly for the height of the oven and downwardly below the bottom of said flue and forming a chamber open at the bottom to the atmosphere; 85 and a gas burner arranged in said chamber and disposed centrally under said flue.

5. In a combined coal and gas stove, a coal fire box, an oven, a flue for the gases of combustion of the coal fire arranged over 90 the oven, a coal gas flue arranged below the oven, a flue arranged in the rear of the oven connecting said flues, said flue below the oven being of less width than the oven whereby flues opening into the oven are provided on opposite sides of said flue below the oven and a gas burner arranged below the said latter flue.

6. In a combined coal and gas stove, an oven, a flue for the gases of combustion of the coal fire arranged below said oven, a chamber below said flue communicating with the oven, a gas burner in said chamber, a top lining in said oven spaced from the top oven plate and forming a flue above said 105 lining, said lining being provided with apertures adjacent its forward end, a flue adapted to be connected with the chimney, and an apertured main oven back plate separating the latter flue from the flue above the oven 110 lining.

7. In a combined coal and gas stove, an oven, a flue for the gases of combustion of the coal fire arranged below said oven, a chamber below said flue communicating with the oven, a gas burner in said chamber, a main back plate for said oven and a flue behind said back plate adapted for connection with the chimney, said back plate being apertured to connect the oven with 115 the latter flue.

8. In a combined coal and gas stove, a front oven plate forming the front of the oven, a back oven plate forming the back of the oven, a bottom oven plate spaced from 125 said front and back oven plates, a flue for the gases of combustion of the coal fire arranged below said bottom oven plate and

being of less width than the oven, the side walls of the flue being spaced from the front and back oven plates, whereby flues are provided between the front and back oven plates and the side walls of the coal gas flue, and a gas burner arranged below the coal gas flue.

In testimony whereof, I have hereunto set my hand at San Francisco, California, this 6th day of July, 1917.

JOHN H. SATTLER.
